UNITED STATES PATENT OFFICE.

L. HENRY SMITH, OF SALEM, NEW JERSEY, ASSIGNOR OF ONE-HALF TO
THOMAS B. STARR AND RICHARD T. STARR, BOTH OF SAME PLACE.

CAN-FILLING MACHINE.

SPECIFICATION forming part of Letters Patent No. 289,155, dated November 27, 1883.

Application filed August 29, 1883. (No model.)

To all whom it may concern:

Be it known that I, L. HENRY SMITH, a citizen of the United States, residing in Salem, Salem county, New Jersey, have invented certain Improvements in Can-Filling Machines, of which the following is a specification.

My invention relates to machines for filling cans with tomatoes or other vegetables or with fruit; the object of my invention being to facilitate the operation of the plunger, to provide a close joint at the top of the can, and to permit the free escape of air or surplus material from the can during the filling operation. These objects I attain in the manner hereinafter set forth, reference being had to the accompanying drawings, in which—

Figure 1, Sheet 1, is a side view, partly in section, of my improved can-filling machine; Fig. 2, Sheet 2, a plan view of part of the same; Fig. 3, a plan view on the line 1 2, Fig. 1; Fig. 3^a, a detached view of part of Fig. 1, with some of the parts in a different position; Fig. 4, a front view of part of the machine; Fig. 5, Sheet 3, a plan view of the valve; and Fig. 6, a vertical section of the can-holder, valve, and valve-guide. Figs. 4, 5, and 6 are on a larger scale than Figs. 1, 2, 3, and 3^a.

A A are the opposite side frames of the machine, having suitable transverse supports for the filling-spout B, straining-box D, valve-guide E, and can-carrier F, and transverse rods z, to which are hung a treadle, G, and a pair of levers, H, the treadle being connected to the levers by rods G', and the levers having rods H', whereby they are connected to a cross-head, H², guided in the side frames and carrying the plunger I. The plunger works freely in the filling-spout B, and the latter communicates through a funnel, B', with the straining-box D, which has a perforated false bottom, D', so that the greater portion of the juice is drained from the vegetables or fruit deposited in the box, and permitted to pass off through a pipe, a.

The can-carrier consists of a table, F, having wheels b, which are adapted to rails d on a platform, J, the latter being supported upon set-screws f, carried by the transverse bar f' of the frame, whereby said platform can be adjusted to any height which the size of the can may suggest, the platform being guided in its

movement by a dowel-pin, f². The rails d have inclined portions d', so that as the table F is moved outward it will fall to a certain extent, there being a corresponding rise of the table as it is pushed inward, stops g g', on the bar f', serving to limit the movement of the table in both directions. An adjustable gage-plate, h, on the bar f' and a plate, i, likewise adjustable on the table F, serve to insure such an adjustment of the can x that when the table has been pushed inward to its full extent, the opening in the can will be in line with the mouth of the filling-spout. Sliding on the valve-guide E is a valve, M, which is connected by a rod, k, to an arm, k', on a rock-shaft, m, another rod, n, connecting said arm to the gage-plate i. To the latter is also attached a rod, p, which is guided in a bracket, p', on the frame, and is acted on by a spring, p², the tendency of which is to push the table F outward. The valve M has an opening, s, of the same diameter as the mouth of the filling-spout, and an opening, s', in the valve-guide, E, a flange, s², surrounding the opening s, so as to form a passage for the vegetables or fruit from the spout to the can. On the under side of the valve is a plate, N, which is guided on the flange s² and on the supporting-pins t, and is free to move vertically to a limited extent independently of the valve, the under side of this plate carrying a ring, w, of rubber or other elastic or semi-elastic material for forming a joint with the top of the can. The weight of the plate N may be relied upon to cause it to press on the can, or suitable springs may be interposed between said plate and the valve. In the valve is a chamber, y, and in the flange s² is an annular passage, y', communicating therewith, a passage of large area, and extending entirely around the mouth of the can, being thus provided for the escape of the air or surplus material during the filling of the can.

The operation of the machine is as follows: The can is applied to the table F while the latter is in the position shown in Fig. 3^a, the valve being closed and the plunger I elevated. The can and supporting-table are then pushed inward, the rollers b running on the rails d, so as to elevate the can and press the top of the same firmly against the ring w on the plate N.

The valve M, owing to its connection with the gage-plate *i*, is reciprocated, so as to bring the opening *s* into line with the mouth of the filling-spout, and thus permit the discharge of 5 the fruit or vegetables into the can on the descent of the plunger I, which is effected by pressure on the treadle G. As the can is filled the air and surplus material escape therefrom through the passage *y'* and chamber *y*, being 10 carried from the latter through a flexible pipe to any suitable receptacle. When the can is filled, the table F is allowed to move outward, the valve M following this movement, so as to close the filling-spout, and the can *x* falling, 15 so as to free it from contact with the ring *w* on the plate N, and thus permit its removal and the application of an empty can to the table F. By weighting the levers H and treadle G the weight of the plunger and its connections 20 is balanced much more effectively than with the usual springs, the tension of which is greatest when the plunger is depressed, so that it tends to interfere with the desired forcible descent of the plunger, whereas the 25 momentum acquired by the weights on the levers and treadle tends to aid rather than detract from the forcible thrust of the plunger. The levers only or the treadle only may be weighted, if desired; but I prefer to weight 30 both, as shown.

By providing the valve with a loose plate carrying the packing-ring slight variations in the height of the cans is compensated for—that is to say, variations other than the general variations for which the adjustable platform J is intended.

I claim as my invention—

1. The combination of the filling-spout and plunger of a can-filling machine with a longitudinally-movable can-holding table, F, and 40 inclined supporting-rails *d* therefor, as set forth.

2. The combination of the filling-spout and plunger of the machine with inclined supporting-rails *d*, a platform, J, carrying the same, 45 and adjusting set-screws *f*, as set forth.

3. The combination of the valve of a can-filling machine with a yielding plate for making a joint with the top of the can, as set forth.

4. The valve M, having a discharge-chamber, *y*, formed therein for the escape of air and juices from the can, as set forth. 50

5. The valve M, having the discharge-chamber *y*, the opening *s*, and the annular flange *s'*, with passage *y'* communicating with the 55 chamber *y*, as set forth.

6. The combination of the can-carrier F, the filling-spout, the valve M and connections, substantially as described, between the valve and can-carrier, whereby the reciprocation of 60 the valve is effected simultaneously with the adjustment of the can, as set forth.

7. The combination of the plunger I with the actuating devices, counterbalanced as described, whereby the momentum of the balancing-weights adds to the force of the plunger, as set forth. 65

In testimony whereof I have signed my name to this specification in the presence of two subscribing witnesses.

L. HENRY SMITH.
